(57) **CLAIM**

The ornamental design for a dispenser base, as shown and described.

DESCRIPTION

FIG. 1 is a top, front, left perspective view of a dispenser base showing the new design.

FIG. 2 is a top view of the dispenser base showing the new design.

FIG. 3 is a bottom view of the dispenser base showing the new design.

FIG. 4 is a left view of the dispenser base showing the new design.

FIG. 5 is a right view of the dispenser base showing the new design.

FIG. 6 is a front view of the dispenser base showing the new design; and,

FIG. 7 is a rear view of the dispenser base showing the new design.

The broken lines in the drawings depict portions of the dispenser base that form no part of the claimed design.

1 Claim, 5 Drawing Sheets
